UNITED STATES PATENT OFFICE

SAMUEL J. WOLFSON, OF EVERETT, MASSACHUSETTS, ASSIGNOR TO CONCRETE-WOOD FLOOR CLIP CO., INC.

FLOORING

Application filed May 20, 1930. Serial No. 454,047.

The present invention relates, in its broader aspects, to flooring, in general. More specifically, this invention has particular relation to that type of flooring commonly known as parquet flooring or parquetry.

Among the objects of the present invention are: to provide a novel and improved unit of parquet flooring; to provide simple, novel and improved means for holding the several component strips of each unit securely together; to provide a novel, efficient and inexpensive fastener for firmly securing a number of the parquetry units in place on an under-floor without exposing the fastener or piecing or leaving unsightly nail-holes in the parquetry; and to provide a parquetry unit and coacting fastener of the character above-described which shall be especially adapted to be used in connection with concrete floors.

To the accomplishment of these objects and such others as may hereinafter appear, the various features of the present invention relate to certain devices, combinations, and arrangements of parts fully set forth herein-after, the advantages of which will be readily understood by those skilled in the art to which this invention pertains.

The various features of the invention will be best understood from an inspection of the accompanying sheets of drawings illustrating the preferred forms of the invention.

In the said drawings,

Fig. 1 is a top plan view of a unit of parquetry embodying the present invention, and 35 a broken top plan view of an adjacent unit;

Fig. 2 is a perspective view, illustrating the manner in which the fastener of the present invention cooperates with the parquetry units;

40 Fig. 3 is a partial end view of one of the parquetry units looking in the direction of arrow A in Fig. 1;

Fig. 4 is a top plan view of the strip-secur-

ing device;

45 Fig. 5 is a sectional view taken along line 5-5 of Fig. 4; and

Fig. 6 is a view similar to Fig. 5, but illustrating a modified form of the invention.

Similar reference numerals refer to similar parts throughout the several views.

According to the present invention, each unit of parquetry, indicated in general at 10 (in Fig. 1), may comprise a plurality of strips 11, 12, 13 and 14 of suitable and preferably relatively thin high-grade wood. The strips are illustrated in the drawings as being of such length and width as to form a square unit of parquetry when assembled. However, it is obvious that the number and dimensions of the strips may be varied to suit different tastes and for different purposes.

In order to enable the several strips 11, 12, 13 and 14 to be securely fastened together to form a unit of parquetry, they are provided with a suitable number of transversely-extending spaced grooves 15 of a suitable depth, as hereinafter explained in greater detail. The number of such grooves employed will obviously depend on the shape and size of the unit of flooring.

Relatively thin metallic strips 16, having saw-tooth edges 17 and tonguelike ends 17', are adapted to be disposed in the grooves 15 with the teeth of the edges 17 biting into the adjacent strips 11, 12, 13 and 14. In this way the several strips are effectively bound together as a unit to successfully resist forces acting thereon in any direction and tending to displace them relative to each other.

Each metallic strip 16 is originally transversely bent, as is shown in dotted lines in Fig. 3, so that its effective original width is equal to that of its cooperating groove 15. By hammering or otherwise exerting a pressure on the face of the strip 16 in the direction of the arrow B (Fig. 3), the strip is flattened out and its saw-toothed edges are driven into biting relation with the adjacent wooden strips, as shown.

The edges of each unit 10 of parquetry are severally milled to provide them with tongue-receiving grooves 18 extending substantially the full length of each edge. Each unit 10 is also rabbeted to form grooves 19 around the bottom thereof. Grooves 19 are preferably made about one and a half times as wide as grooves 18, as shown. These grooves 18 and 19, in effect, form tongues 20 between them. The ends of tongues 20 are 100

cut short so that they do not extend clear out to the edges of the parquetry units for a purpose which will hereinafter appear.

Fasteners are provided for securely binding the units of parquetry to the sub-flooring and to each other. These fasteners are preferably bent from sheet metal to the form clearly shown in Figs. 2 and 5. They preferably comprise horizontal two-ply tongues 21 adapted to be snugly received in the grooves 18 of the parquetry units, and base or supporting portions 22 extending laterally from one side of the bottom of vertical portions 23.

The vertical portions 23 are adapted to be received between the shortened tongues 20, as is clearly shown in Fig. 5, and the bases 22 are substantially coextensive with and adapted to be received in the rabbeted grooves 19.

The base portions 22 extend only from one side of the vertical members 23, and with the corresponding tongues 21 form sockets adapted to receive the tongues 20 of adjacent parquetry units.

Nails, or other suitable fastening elements, may be driven directly into the under-flooring through the base portions 22. The tongues 21, vertical portions 23 and bases 22 are continuous and longitudinally coextensive with each other and with the edges of the units 10, as shown in Fig. 1. In this manner a firm support is provided which extends along the entire length of each unit of parquetry.

The grooves 15 extend upwardly to the bottom of grooves 18. The tongues 17 of the fasteners 16 extend into the grooves 18 to take the place of those portions of tongues 20 which are removed in the formation of grooves 15. In this way, a substantially continuous support is afforded to the corresponding tongue 21.

In laying the floor, the under-flooring is first covered with a layer of mastic or the like. Then a unit of parquetry is laid thereon. A fastener tongue is inserted into the groove 18 of each exposed edge of the unit so that the base portions extend outwardly. Nails or the like are then driven into the concrete sub-flooring through the base portions. Then another unit of parquetry 10 with its component strips 11, 12, 13 and 14 disposed transversely to the strips of the first unit, is laid in place. The groove 18 of the second unit receives the exposed tongue of the fastener, the base portion 22 fitting into the rabbet 19. This process is continued until the entire flooring is laid.

In Fig. 6, a modification of the invention is shown. This modification differs from the hereinbefore described embodiment only in that the rabbet 19 is omitted, the unit of parquetry resting directly on the base portion 22 of the contiguous fastener.

Base portions 22 of the fasteners are preferably provided with a plurality of X-shaped cut-outs 24 between the several nail-holes 25. In case the under-flooring is of a character with which nails may not be used, the X-shaped cut-outs 24 are adapted to receive mastic and securely hold the fasteners down on the mastic-covered under-flooring.

It is obvious that the fastener above described is adapted to be used in the laying of strip flooring on concrete under-flooring as well as with parquet flooring, and also in the attachment of panels to walls.

I claim:

1. In combination, a unit of parquetry comprising a plurality of strips of flooring material, a second unit of parquetry comprising a plurality of strips of flooring material, said last-named strips extending in a direction transversely to said first-named strips, each of said units having a groove extending therearound, a one-piece sheet metal fastening device disposed between said units and comprising a base portion, a vertical portion disposed at one side of said base portion, and a pair of tongues, one of said tongues being disposed in the groove of one of said units, and the other of said tongues being disposed in the groove of the other unit, each of said tongues, base portion and vertical portion being continuous and longitudinally coextensive.

2. A one-piece sheet metal fastening device adapted to be used with flooring comprising a base portion, a vertical portion extending upwardly from said base portion at one side thereof, and a pair of tongues extending outwardly from the top of said vertical position, said base portion, vertical portion and tongues being longitudinally coextensive and continuous.

3. A one-piece sheet metal fastening clip of the character described comprising a base, a vertical member extending from one edge of said base substantially at right angles thereto, said clip being bent laterally from the top of said vertical member in the direction in which base extends to form the lower ply of a tongue, said ply bent back upon itself to form the upper ply of the said tongue and the upper ply of a second and oppositely-extending tongue, the free end of said last-named ply being bent back upon itself to form the lower ply of said second tongue.

SAMUEL J. WOLFSON.
